UNITED STATES PATENT OFFICE.

FRANÇOIS R. MARCEL, OF BROOKLYN, NEW YORK.

CURLING PIN FOR PERMANENT HAIR WAVING.

Application filed July 22, 1926. Serial No. 124,141.

In my Letters Patent numbered 1,368,181 dated February 8, 1921, I showed and described a novel form of curling pin on which a lock of hair may be wound tightly 5 for the purpose of being treated by means of suitable chemicals, and then baked by means of a heater placed over the rod and the lock of hair in order to form in the hair what is generally known as a permanent 10 wave. My present invention is preferably embodied in a pin containing the subject matter of said patent, although the present invention is not limited to a pin of that character. In winding hair upon a curling 15 pin preparatory to forming a permanent wave, it is necessary to have all portions of the lock of hair under tension as it is necessary to have the hair under tension while undergoing treatment with chemicals, 20 and with heat, in order to make the wave permanent. In the pins heretofore used, including that shown in my said patent, the lock of hair close to the head is fastened to one end of the pin and it is then wound 25 upon the sleeve which is revolvably mounted on the rod; and the free end of the lock of hair is then tied to the sleeve, after which a relative rotation of the sleeve and rod causes the lock of hair to be drawn close to 30 the pin. There is usually a clutch device employed for locking the rod and sleeve after the hair has been tightened in this manner. I have found that with a round sleeve on the curling pin some portions of 35 the lock of hair are drawn tightly, whereas other portions are not put under tension or are put under very light tension, and as a result an imperfect wave is formed. It is more of a curl than a true wave, and of 40 course the latter is the desirable object to be attained. It is especially difficult with such devices to form what is known as a flat wave, as distinguished from a round wave. In the present invention I provide 45 means for tightening the lock of hair upon the pin, the action of which is to draw in or tighten the inner layers of hair contained in the lock, and after these have been tightly drawn in, the outer layers are also drawn 50 tight either by the pin or by exerting a twisting action with the hand. As a result the entire lock of hair is put under greater tension than heretofore and a more perfect and lasting wave is formed by the subsequent waving process. In addition to the

above I have provided a very simple means for attaching the lock of hair adjacent the head to one end of the pin, securely, and without the use of a tie string, so that the operation of attaching this part of the hair 60 to the pin is much quicker, eliminating the tedious operation of tying the hair upon the curler.

In the drawing forming part of this application,

Figure 1 is an elevation of a curling pin embodying my invention,

Figure 2 is a similar view showing a modified form of the invention,

Figure 3 is an enlarged plan view of one 70 end of the pin, illustrating the hook for attaching the lock of hair,

Figure 4 is an elevation of the device with the lock of hair wound thereon to illustrate the mode of use,

Figure 5 is a sectional view taken on the line 5—5 of Figure 1,

Figure 6 is a sectional view taken on the line 6—6 of Figure 2,

Figure 7 is a sectional view corresponding with Figure 5 but showing a modified form of device, and

Figure 8 is an enlarged elevation of a portion of the pin shown in Figure 2.

The present device consists primarily of 85 two relatively revolvable members, one turning upon the other, the two forming a pin on which the lock of hair is adapted to be wound. In the drawing I have shown a solid rod or member 1 which is one of these 90 component parts, and on one end of this rod there is a head 2 which is adapted to be engaged or gripped by a pair of pliers for holding the same against turning while the second or outer member is revolved in relation thereto. At the other end, this rod has an enlarged member 3 from which projects a member constituting a loop. In the drawings this is shown as a continuation of a reduced neck integral with the member 3 which 100 curves at 4 and returns at 5 over the member 3 to form a loop having an opening 6 within which the hair is adapted to be pushed. The free end 7 of this hook is enlarged laterally and is wider than the neck 105 or loop 4.

The outer member of the pin comprises a sleeve 8 which is preferably knurled at one end as shown at 9 in order to be gripped by the fingers; and this sleeve member fits 110

over the rod 1 on which it is adapted to revolve, and it is slightly shorter than the distance between the shoulder 10 of the head and the shoulder 11 of the member 3.

5 There is a clutch member for setting the sleeve and rod against relative rotation but I have not shown the same in detail for the reason that the same clutch as is shown in my said patent may be used for the 10 present device. In my said patent the sleeve is shown with a circular periphery but I have found that the same does not tighten the lock of hair in the efficient manner than it can be tightened with the present device. In the form shown in Figure 15 1 the sleeve 8 is flattened on opposite faces by means of grooves 12 extending longitudinally, preferably at opposite sides of the sleeve. The grooves may be formed by removing a portion of the sleeve, if desired, 20 and in one form of the invention, or that represented by Figures 2, 7 both the sleeve and a portion of the rod within it are flattened on opposite faces to provide the flat 25 surfaces 13, 14. The rod and sleeve may be so positioned that these flat surfaces of the rod and sleeve register as shown in Figure 5.

30 In placing the lock of hair upon the curler the lock is first combed out from the head and then it is passed under the hook 5, thence over the top of the hook, as shown at 35 16 in Figure 4, thence around the member 3 and this turn 17 is then pushed along the member 3 until it is placed under the end of the hook 5 as shown in Figure 4 to keep the turn 16 from shifting. The lock of hair is then repeatedly wound around the member 3 along the sleeve 8, and if desired one 40 turn may partly overlap another until the end of the lock of hair has been reached, whereupon a tie string 18 is wound around the loose end and the curler and is tied. The operator then grasps the member 2 with 45 a pair of pliers to hold the rod from turning, and grips the knurled portion 9 of the sleeve and turns the sleeve in relation to the rod, so that the lock of hair is twisted and tightened upon the curler. I have found 50 that with the flattened sides on the curler it has a tendency to tighten the interior hair, or interior layers of the lock of hair, first, after which subsequent layers gradually tighten, and if the outer portion is not 55 sufficiently tight when the sleeve has been turned as far as possible, the operator may grasp the hair around the sleeve adjacent the spring 18 and twist the lock of hair until the outermost layers become very tight. 60 It will be understood that when the sleeve is being revolved in the above described operation, it is pressed toward the shoulder 11 to release the clutch and afterwards it is moved toward the shoulder 10 to engage the 65 clutch and hold the rod and sleeve against

relative rotation. A curler constructed with the flat faces as described herein, operates to tighten the lock of hair at all portions to a much higher degree than it has been possible to obtain with round curlers, 70 due to the drawing action on the interior layer of the hair. When the hair is placed under greater tension in this manner, it is possible to obtain a more permanent wave in the subsequent process, and in addition 75 the wave has a much more definite formation than with other types of curlers. In fact, it is possible to obtain a true wave (which is the desired result) as distinguished from a short, kinky curl. While I 80 have shown flat faces on opposite sides of the curler I do not wish to limit my invention to this particular number, shape and disposition of faces, although this has proven successful in operation. 85

The construction may be modified as shown in Figure 7 by forming the flat faces to extend only through the wall of the sleeve, as shown at 19 in which case the rod within the sleeve remains cylindrical. In Figures 90 2, 6, 8 I have shown the device in another modified form. In this form I have provided a series of indentations or grooves 95 20 extending crosswise of the sleeve and rod, the individual grooves being slightly spaced apart and extending throughout the active portion of the sleeve. At the opposite side of the curler in this construction I have shown other grooves 21 extending crosswise 100 of the curler, and in the preferred construction these are not arranged directly opposite the grooves 20 but are offset or staggered in relation thereto, as shown in Figure 8. This device is used in the same manner as the one first described and when the lock of 105 hair is wound around the sleeve it passes over the surface formed by the grooves 20, 21 and when the sleeve is turned in relation to the rod the edges of these surfaces serve to tighten the hair by acting primarily on 110 the inner layers. From this it is apparent that it is not necessary that the curler be provided with flat surfaces, but that any formation which will deviate from a circular 115 face and provide edges for working the inner layers of the hair, will accomplish the result desired. 115

Having described my invention, what I claim is:

1. A curling pin around which a lock of hair is adapted to be wound for waving, comprising relatively revolvable members around which a lock of hair is adapted to be wound, a substantial part of the length of said curler being non-circular in cross section for the purpose set forth. 120
2. A curling pin comprising relatively revolvable members around which a lock of hair is adapted to be wound, said pin having one or more grooves in the outer surface 125 130

forming edges adapted to act upon the inner layers of hair wound upon said pin for the purpose of tightening the lock of hair upon said pin.

5 3. A curling pin comprising relatively revolvable members arranged one within the other and around which a lock of hair is adapted to be wound, the exterior of said pin being partially circular and having one 10 or more grooves to provide edges adapted for the purpose set forth.

4. A curling pin comprising a rod member, a sleeve fitting over and revolvable upon said rod member and around which a lock of hair is adapted to be wound, said rod and 15 sleeve members having flattened portions to form edges adapted to act upon the lock of hair to tighten the same upon the pin.

5. A curling pin comprising relatively revolvable members arranged one within the other and around which a lock of hair is adapted to be wound, said pin having 20

grooves extending crosswise thereof for the purpose set forth.

6. A curling pin comprising relatively revolvable members around which a lock of hair is adapted to be wound, said pin having laterally extending grooves at one side thereof and having other grooves arranged at the opposite side of the pin and in staggered 25 30 relation to said first grooves.

7. A curling pin comprising relatively revolvable members around which a lock of hair is adapted to be wound, a hook extending from said pin adjacent one end thereof 35 and bent backwardly over the body of the pin whereby the lock of hair may be wound over said hook and between the hook and said body of the pin, said hook having its free end laterally enlarged for the purpose 40 described.

Signed at the city, county and State of New York, this 7th day of July, 1926.

FRANÇOIS R. MARCEL.
